UNITED STATES PATENT OFFICE.

JAMES S. JONES AND EDWIN A. SCOTT, OF BEGGS, OKLAHOMA.

GASOLINE-SUPPLYING ATTACHMENT.

Application filed October 13, 1922. Serial No. 594,263.

To all whom it may concern:

Be it known that we, JAMES S. JONES and EDWIN A. SCOTT, citizens of the United States, residing at Beggs, in the county of Okmulgee, State of Oklahoma, have invented a new and useful Gasoline-Supplying Attachment, of which the following is a specification.

It is a well known fact that when a motor 10 propelled vehicle, provided with an ordinary gravity feed for the carburetor, ascends a steep hill, the supply of fuel for the carburetor often fails. The foregoing being understood, this invention aims to provide 15 novel means whereby fuel will be delivered to the carburetor no matter how steep be the ascent, novel means being provided for segregating from the fuel, any water which may be therein.

It is within the province of the disclosure 20 to improve generally and to enhance the utility of devices of that type to which the invention appertains.

With the above and other objects in view, 25 which will appear as the description proceeds, the invention resides in the combination and arrangement of parts and in the details of construction hereinafter described and claimed, it being understood that, within 30 the scope of what is claimed, changes in the precise embodiment of the invention shown can be made without departing from the spirit of the invention.

In the accompanying drawings:

Figure 1 shows in longitudinal section, a 35 device constructed in accordance with the invention; Figure 2 is a longitudinal section of the auxiliary tank and attendant parts; Figure 3 is a cross section on the line 3—3 of Figure 2.

In the drawings, there is shown a portion 40 of a motor propelled vehicle including a dash board 1, a hood 2, a carburetor 3, a main fuel tank 4 and a chassis bar 5.

In carrying out the invention, an auxiliary 45 tank 6 is located in advance of the carburetor 3 and is held by yokes 7 and securing elements 8, or in any other suitable way, upon the chassis bar 5. The auxiliary tank 6 has 50 a downwardly and forwardly inclined bottom 9, defining a water pocket 10 at the forward end of the tank. Water may be drawn off from the pocket 10 through a drain cock 11 carried by the bottom of the tank. A

baffle plate 12 extends across the auxiliary 55 tank 6 from side to side and extends for-

wardly from the rear wall of the tank, a water pocket 14 existing, at the rear end of the tank, below the baffle plate 12. A fuel supply conduit 15 leads forwardly from the main tank 4 and enters the rear end of the auxiliary tank 6. The fuel supply conduit 15 has an upwardly inclined end located closely adjacent to the top of the auxiliary tank 6. A delivery conduit 17 is provided, 60 one end of the delivery conduit entering the rear end of the auxiliary tank 6 at a point immediately above the baffle plate 12. The other end of the delivery conduit 17 is connected to the carburetor 3. The numeral 18 65 marks a vent pipe entering the rear end of the auxiliary tank 6 and extended forwardly below the top of the auxiliary tank. A clip 19 may be used to secure the end 16 of the pipe 15, and the vent pipe 18, to the upper 70 wall of the tank 6. The vent pipe 18 may be arranged in any desired way. If preferred, it may be extended upwardly beneath the hood 2, in front of the dash board 1.

In practical operation, fuel proceeding 75 from the tank 4 traverses the supply conduit 15 and flows into the auxiliary tank 6, through the end 16 of the conduit 15. The fuel, having been deposited in the auxiliary tank 6, finds its way to the carburetor 3, by 80 way of the delivery conduit 17. Any water in the fuel will gravitate to the inclined bottom 9, and following the bottom 9 will collect in the pocket 10. The water may be drawn off from the pocket 10 through the 85 drain cock 11. When the vehicle ascends a steep grade, the fuel in the tank 6 will flow backwardly through the conduit 17 to the carburetor as freely as though the vehicle were traveling upon the level. When the vehicle is ascending a steep grade, water which 90 may have accumulated in the pocket 10 will flow rearwardly, and be caught in the pocket 14 existing beneath the baffle plate 12. Thus, when the vehicle is going up-grade, the water 95 in the fuel cannot find its way into the delivery conduit 17, and thence, to the carburetor 3. The necessary vent is provided through the pipe 18, and, since this pipe is located adjacent the top of the auxiliary tank 100 6, an adequate air inlet will always be provided.

What is claimed is:

1. In a device of the class described, a main fuel tank; a carburetor; an auxiliary fuel tank located in advance of the carburetor and having a downwardly and forwardly in-

clined bottom defining a water pocket at the forward end of the auxiliary tank, means for draining the pocket, a supply conduit leading from the main tank to the auxiliary tank; and a delivery conduit leading from the auxiliary tank to the carbureter.

2. In a device of the class described, a main fuel tank; a carbureter; an auxiliary fuel tank located in advance of the carbureter and provided at its rear end with a baffle defining a water pocket; a supply conduit leading from the main tank to the auxiliary tank; and a delivery conduit leading from the auxiliary tank to the carbureter, the delivery conduit communicating with the auxiliary tank above the baffle.

3. In a device of the class described, a main fuel tank; a carbureter; an auxiliary fuel tank located in advance of the carbureter and having a downwardly and forwardly in-

clined bottom defining a water pocket at the forward end of the auxiliary tank; means for draining the pocket; a baffle mounted in the rear end of the auxiliary tank and defining a pocket for the collection of water; 25 a supply conduit leading from the main tank to the auxiliary tank; and a delivery tank leading from the auxiliary tank to the carbureter, the delivery conduit communicating with the auxiliary tank at a point above the 30 baffle.

In testimony that we claim the foregoing as our own, we have hereto affixed our signatures in the presence of two witnesses.

EDWIN A. SCOTT.
JAMES S. JONES.
